(57) **CLAIM**

The ornamental design for a rack assembly, as shown and described.

DESCRIPTION

FIG. 1 is a top perspective view of a rack assembly;

FIG. 2 is a front elevational view thereof;

FIG. 3 is a top plan view thereof;

FIG. 4 is a bottom plan view thereof;

FIG. 5 is a rear elevational view thereof; and,

FIG. 6 is a left elevational view thereof, the right elevational being a mirror image thereof.

The broken lines in the drawings show portions of the rack assembly and form no part of the claimed design.
